Inventor,

Clarence Boosus

United States Patent Office.

CLARENCE BROSIUS, OF HANCOCK, MARYLAND.

Letters Patent No. 74,493, dated February 18, 1868.

IMPROVEMENT IN SKID FOR ELEVATING AND LOWERING BARRELS, &c.

The Schedule referred to in these Letters Patent and making part of the same.

Be it known that I, CLARENCE BROSIUS, of the town of Hancock, in the county of Washington, and State of Maryland, have invented a new and improved Apparatus for Elevating and Lowering Hogsheads, Barrels, Boxes, or any other heavy articles; and I do hereby declare that the following is a full and exact description thereof, reference being had to the accompanying drawings, and to the letters of reference marked thereon.

My invention consists in the construction of a stationary skid and slide, and stays, for the accomplishment of said purpose.

To enable any one to make use of my invention, I will proceed to describe its construction and operation.

I construct a stationary skid, marked A, as shown by the accompanying drawing; also a slide, with pointed handles on the upper end, marked B; a rope or chain, marked C; and stays, marked D. The skid A is placed with its top resting at the level or plane to which the article is to be raised, or from which it is to be lowered, the lower end of the skid resting on the plane to which the article is to be lowered or from which it is to be raised, the skid to be placed at any angle convenient. The rope or chain C is fastened to a clef attached to the centre of lower cross-piece of slide B, marked *a*, and is thence carried to and over a small pulley, marked *b*, which pulley is inserted in a mortise made in cross-piece E, which turns on its axis, let into upper end of skid A. The rope or chain C then passes over a small pulley, working in a mortise made in the centre of the lower cross-piece of slide B, thence to and over a larger pulley working in the upper part of the mortise in cross-piece E', marked *c*, thence to and over a small pulley working in a mortise let into the side piece of skid A. The slide B has four wheels, two marked *e e*, set in the lower ends of slide B, and two of half the size of lower wheels, working half in a mortise let into the lower side of side pieces of slide B above the upper cross-piece of said slide B. The upper part of the side pieces of slide B are perforated with two or more holes, in which are inserted the stays D D when used. The slide B works in a groove made in side pieces of skid A.

When the apparatus is to be used for lowering an article, the slide B is drawn up the groove in skid A until the wheels *e e* rest in the upper part of said groove, and the slide on the level from which the article is to be lowered. The article is then placed on slide B, and secured with stays D D, and then lowered by the operator by means of rope or chain C. To raise an article, the slide B is lowered in grooves of skid A until the pointed handles of upper part of slide rest in the lower part of said grooves, and the slide itself on the plane from which the article is to be raised. The article is then placed on the slide, stayed with stays D D, and then raised by the operator by means of rope or chain C, working as before described.

What I claim as my invention, and desire to secure by Letters Patent, is—

The skid, slide, and stays, as described and set forth.

CLARENCE BROSIUS.
